Invention,

Albert A. Brown,

by Jacob Abbott Morris
his Attorney.

UNITED STATES PATENT OFFICE.

ALBERT A. BROWN, OF CHICAGO, ILLINOIS.

POCKET.

1,128,941.

Specification of Letters Patent. Patented Feb. 16, 1915.

Application filed February 20, 1914. Serial No. 819,930.

To all whom it may concern:

Be it known that I, ALBERT A. BROWN, a citizen of the United States, and a resident of the city of Chicago, county of Cook, and State of Illinois, have invented certain new and useful Improvements in Pockets, of which the following is a specification.

My invention relates to improvements in pockets especially adapted to be applied to stockings and has for its object the provision of an improved construction of this character which is simple and efficient in use.

The invention consists in the combinations and arrangements of parts hereinafter described and claimed.

The invention will be best understood by reference to the accompanying drawing forming a part of this specification, and in which—

20 Figure 1 is a side view of a stocking provided with a pocket embodying my invention, Fig. 2, an enlarged section taken on line 2—2 of Fig. 1, and Fig. 3, an enlarged section taken on line 3—3 of Fig. 1.

25 The preferred form of construction as illustrated in the drawing comprises a pocket 4 formed of cloth or other suitable material and stitched along its side and bottom edges to a stocking 5 by a line of stitches 6. This forms another pocket between the rear of pocket 4 and the outer surface of stocking 5 which is adapted to contain bills or other articles not easily dislodged. Pocket 4 is provided with a closing flap 8 arranged to fold over the outer face thereof and flap 8 is provided with a pocket 9 on its inner face. An elastic band 10 is arranged to hold flap 8 in closed position.

The construction set forth furnishes three

separate and distinct pockets and the elastic 40 band is so arranged as to hold articles securely in all of said pockets. The construction is very simple and can be made at a trifling cost.

While I have illustrated and described the 45 preferred form of construction for carrying my invention into effect, this is capable of variation and modification without departing from the spirit of the invention. I, therefore, do not wish to be limited to the 50 precise details of construction set forth, but desire to avail myself of such variations and modifications as come within the scope of the appended claims.

Having described my invention what I 55 claim as new and desire to secure by Letters Patent is:

1. The combination with a backing of a flexible pocket secured thereto along its side and bottom edges to form another pocket; a 60 closing flap for said pocket; and an elastic band arranged to hold said flap closed, substantially as described.

2. The combination with a stocking, of a flexible pocket secured thereto along its side 65 and bottom edges to form another pocket; a closing flap for said pocket; a pocket on the inner side of said flap; and an elastic band arranged to hold said flap closed, substantially as described.

In testimony whereof I have signed my name to this specification in the presence of two subscribing witnesses.

ALBERT A. BROWN.
